UNITED STATES PATENT OFFICE.

LOUIS G. JUSTH, OF CHICAGO, ILLINOIS, ASSIGNOR OF ONE-FOURTH TO NAPERVILLE LOUNGE COMPANY, OF NAPERVILLE, ILLINOIS, A CORPORATION OF ILLINOIS, AND THREE-FOURTHS TO ALBERT EGER, OF CHICAGO, ILLINOIS.

SOFÁ-BED.

991,069.

Specification of Letters Patent.

Patented May 2, 1911.

Application filed January 21, 1910. Serial No. 539,264.

To all whom it may concern:

Be it known that I, LOUIS G. JUSTH, a citizen of the United States, residing at Chicago, in the county of Cook and State of Illinois, have invented certain Improvements in Sofa-Beds, of which the following is a full and complete specification.

This invention is an improvement in sofa-beds, and relates more especially to that 10 particular class in which the sofa-seat and foldable mattress-frame carried thereby are rotatable within the sofa-frame; whereby either the seat or the folded mattress frame may be brought uppermost, in one or the 15 first instance providing an ordinary form of sofa or davenport and in the other or latter instance permitting the mattress-frame to be extended for the use of the device as a bed.

20 The primary object of my present invention is to provide a sofa-bed structure of this general character with a peculiar form of locking device, by which the rotatable sofa seat is securely locked in position when the 25 parts are arranged in bed form, said locking device being so constructed and arranged that it will be operated automatically by the operation of folding and unfolding the mattress-frame, the latter being provided with 30 a catch for holding it folded upon the sofa-seat.

A further object of the invention is to provide a peculiar form of connection between the seat and sofa-frame, whereby the 35 seat is rotatable and shiftable laterally within the frame and is provided with two spaced-apart points of suspension when arranged in sofa form.

Other objects and advantages of the invention will hereinafter appear, and what I 40 claim as new in the art will be specifically set forth in the appended claims.

In the accompanying drawings, which 45 form a part of this specification: Figure 1 is a side or end elevation of a sofa-bed constructed in accordance with my invention, the parts being arranged in sofa form and the near end of the sofa frame removed. Figs. 2, 3 and 4 are views illustrating the 50 operation of converting the device from sofa to bed form. Fig. 5 is an end view, with the parts arranged to provide a bed. Figs. 6 and 7 are detail views of the means for locking the sofa seat in horizontal posi-

tion when the parts are arranged in bed 55 form. Fig. 8 is a detail view of the catch employed for locking the parts of the mattress frame in folded position. Figs. 9, 10 and 11 illustrate a modification of the means for locking the sofa seat in horizontal position. 60

Like numerals of reference indicate like parts in all the figures of the drawings.

In carrying out my invention I provide in the first place a sofa or davenport frame comprising a back 1, and ends 2, 2, and in connection therewith employ the usual form of sofa-seat 3 having a box-like base 4, at the forward end of which is attached a board 5, forming the front rail of the sofa. 70 The sofa-frame may be of any conventional design, and said frame, as well as the seat, may be suitably upholstered, if desired.

In carrying out my invention the seat is rotatable and movable laterally within the frame, for which purpose I provide at each end of the seat a pair of connecting plates 6 and 7; the plate 6 in the present instance being attached to the seat, and the plate 7 attached to an end 2 of the sofa-frame. The 75 plate 6 is provided with a trunnion 8 bearing in a horizontal slot 9 in the plate 7, and the plate 7 is provided with a headed pin 10 engaging in a curved slot 11 in the plate 6; whereby the seat is rotatable within the sofa-frame upon the trunnions 8 at the ends of said seat, and during such rotatable movement will be shifted laterally by means of the pins 10 engaging in the curved slot 11. One end of this slot is offset, as at 11^a, 90 so that when the seat is in position to form a sofa the headed pins engaging in the offsets will prevent the seat from tilting; and in this position of the seat it will have two 95 separate points of suspension; to wit, the trunnion 8 and the pin 10.

Attached to the underside of the rotatable sofa-seat, and movable therewith, is a mattress-frame comprising three sections, the opposite end sections 12 and 13, and the 100 short intermediate section 14, said sections being pivotally connected to each other so that they may be folded as shown, and supported in connection with the sofa-seat by means of the section 12, which is attached to said seat at one end by means of the short standards 15, and at the other end by straps 16. The sections of the mattress frame are 105

preferably made up of angle-iron, and provided with the usual spring-wire mattress (not shown), upon which is mounted the ordinary felt mattress, as 17.

- 5 The mattress-frame is foldable under the seat and in the rear of the board or front rail 5, and in order to hold said mattress-frame folded during the rotatable movement of the seat and while the device is used 10 as a bed the outer section 13 of said mattress-frame is provided centrally with a catch 18 adapted to engage a keeper 18^a attached to the outer edge of the front rail.

For the purpose of supporting the outer 15 section 13 of the mattress-frame in extended position when the device is arranged in bed form, I provide a supporting-leg 19, which is pivoted to said outer section and to the projecting inner end of which is connected 20 an operating link 20, the other end of said link being pivotally connected materially to the intermediate section 14 of the mattress-frame, whereby said leg will be swung alongside the section 13 when the mattress-frame 25 is folded, and will be opened out or swung to a supporting vertical position when the mattress-frame section 13 is extended for use of the device as a bed.

For the purpose of locking the sofa seat 30 in a reversed horizontal position when the parts are arranged in bed form I provide each stationary connecting-plate 7 with a hole 21, with which is adapted to register a similar hole 22 on the companion connecting-plate 6 attached to the sofa seat, and for 35 each pair of connecting-plates provide a sliding-bolt 23 attached to the sofa-seat and adapted to engage said holes, so as to lock the connecting-plates 6 and 7 together and 40 thereby prevent rotary movement of the plate 6 and sofa seat to which it is attached.

By reference to Fig. 5 it will be seen that when the sofa seat is reversed for use of the device as a bed the trunnion 8 bears in 45 the slot 9 at the forward end of the plate 7, and as the sliding-bolt engages in the rear ends of the plates said sofa seat is supported at two points separated from each other laterally. The sliding-bolt 23 is operated 50 by a lever 24, pivoted, as at 25, to the board or front rail 5 of the sofa-seat, said lever being connected to the bolt through the intervention of a slide-bar 26 and lever 27, the latter being pivoted at its outer end to a 55 bracket 28 on the sofa seat and connected at an intermediate point directly to the bolt by means of a pin engaging a slot 29 in said lever.

A spring 30 is attached at one end to the slide-bar 26 and at the other end to a metal 60 strap 31 attached to the sofa-seat, and this spring is adapted to normally project the bolt into engagement with the registering bolt-holes in the connecting-plates 6 and 7. The upper portion of the operating-lever 24 65 is curved to one side so that it may be de-

pressed for retracting the bolt against the action of the spring, and the end of the lever is bent laterally, as at 24^a, so as to be engaged for depression by the outer end of the mattress-frame section 13 when the latter is folded; thus providing for the automatic operation of the locking device by the operation of folding and unfolding the mattress-frame.

As will be noted, the lateral movement of 75 the sofa-seat imparted by the connecting-plates 6 and 7, is for the purpose of locating the rear end of the seat against the lower end of the upholstered portion of the back, when the device is arranged as a sofa, and 80 to locate the board or front rail 5 a short distance in front of the upholstered back when the device is arranged in bed form, and in this latter instance said board or 85 front rail forms a side piece for the bed to protect the upholstered back.

The operation of the device will be readily understood from the foregoing description in connection with the drawings, for when the parts are arranged in sofa form the mattress-frame will be hidden under the seat, and in the rear of the front rail, the device then having the appearance of an ordinary sofa or davenport, and when it is desired 95 for use as a bed it is only necessary to reverse the sofa-seat to bring the folded mattress-frame uppermost, after which the catch 18 is disengaged permitting the movable sections of said mattress-frame to be extended, the leg 19 being moved automatically to support the outer portion of the mattress frame, and the lever 24 being also automatically operated to lock the connecting-plates 6 and 7 to firmly support the 100 sofa-seat and inner portion of the mattress-frame in horizontal position.

In the modification, shown in Figs. 9, 10 and 11 the bolts, as 32, are located directly in the rear of the board or front-rail 5, and engage keepers 33 on the upper edge of each 110 end piece 2 of the sofa-frame, said bolts being operated in the present instance by means of a slide 34 carrying arms 35, which latter are connected to rods 36 extending 115 from the bolts. The bolts 32 are of the ordinary spring-actuated type, so that they will be normally projected, as shown in Fig. 11, and in order to retract the bolts when the slide 34 is operated by the mattress-frame section 13 the connecting-arms 35 engage in 120 inclined slots 37, as illustrated in Fig. 10. It will be seen, therefore, that in the modification the bolts engage independent keepers instead of the connecting plates, and that 125 the construction of devices for operating said bolts is slightly different from that shown in the other figures of the drawings, though similarly operated by folding and unfolding the mattress-frame.

Having thus described my invention, what 130

I claim as new, and desire to secure by Letters-Patent, is:—

1. In a sofa-bed, the combination with a sofa-frame, seat and foldable mattress-frame carried by the seat, of companion connecting-plates at each end of the seat attached to said seat and adjoining end of the frame, respectively, and having means for supporting the seat rotatably within the frame, a catch for locking the mattress-frame in folded position, and means for locking the seat within the frame, said locking means being arranged for operation by a folding section of the mattress-frame.
2. In a sofa-bed, the combination with a sofa-frame, seat, and foldable mattress-frame carried by the seat, of companion connecting-plates at each end of the seat attached to said seat and adjoining end of the frame, respectively, and having means for supporting the seat rotatably within the frame, and bolt-holes which are adapted to register with each other when the seat is in a certain position, a bolt carried by the seat and adapted to engage the bolt-holes in the connecting-plates, a spring-actuated lever connected to the bolt and having a bent end disposed in the path of a foldable section of the mattress-frame, substantially as herein shown and described.
3. In a sofa-bed, the combination with a sofa-frame, seat and foldable mattress-frame carried by the seat, of companion connecting-plates at each end of the seat attached to said seat and adjoining end of the frame, respectively, and having means for supporting the seat rotatably within the frame and bolt-holes which are adapted to register with each other when the seat is in a certain position, a bolt carried by the seat and adapted to engage the bolt-holes in the connecting-plates, a spring-actuated lever connected to the bolt and having a bent end disposed in the path of a foldable section of the mattress-frame, substantially as herein shown and described.

In testimony whereof I have signed my name to this specification in the presence of two subscribing witnesses.

LOUIS G. JUSTH.
